UNITED STATES PATENT OFFICE

134,991

DESIGN FOR A BAROMETER

Samuel L. Gerson, Bridgeton, N. J.

Application December 8, 1942, Serial No. 108,980

Term of patent 7 years

To all whom it may concern:

Be it known that I, Samuel L. Gerson, a citizen of the United States, residing in Bridgeton, Cumberland County, New Jersey, have invented a new, original, and ornamental Design for a Barometer, of which the following is a specification, reference being had to the accompanying drawing, forming a part thereof.

The figure is a view in perspective of a barometer showing my new design.

I claim:

The ornamental design for a barometer, as shown.

SAMUEL L. GERSON.
